UNITED STATES PATENT OFFICE.

HENRY J. MATHIAS, OF PHILADELPHIA, PENNSYLVANIA.

RANGE.

937,455.

Specification of Letters Patent.

Patented Oct. 19, 1909.

Application filed April 20, 1905. Serial No. 256,678.

To all whom it may concern:

Be it known that I, HENRY J. MATHIAS, a citizen of the Republic of France, residing in the city and county of Philadelphia, State 5 of Pennsylvania, have invented a new and useful Range, of which the following is a specification.

The purpose of my invention is to provide a range of great capacity and convenience. 10 A further object of my invention is to provide a compact advantageous combination of fire pots and a broiling grate.

A further object of my invention is to secure an advantageous distribution of heat 15 without interference with or from the broiling grate.

A further object of my invention is to provide a broiling grate beneath a convertible oven.

20 A further object of my invention is to provide for the removal of the water back without draining the hot water boiler.

It further consists of novel features of construction, all as will be hereinafter fully 25 set forth.

Figure 1 represents a perspective view of my range, a portion of the top front frame of which is broken away. Fig. 2 represents a partial vertical section of Fig. 1 upon line 30 $x-x$ thereof. Fig. 3 represents a vertical section of Fig. 1 upon line $y-y$ thereof. Fig. 4 represents a perspective view of my water back having a portion of the frame thereof broken away. Fig. 5 represents in 35 elevation a front portion of my range with the top removed.

Similar numerals of reference indicate corresponding parts in the figures.

Referring to the drawings:—1 designates 40 the frame of my range which is made up of lower front plates 2 and divided side plates consisting of parts 3, 4 and 5, also back plates 6, top plate 7 and an upper front face 8. The junction between the side plates 45 3 and 4 is formed preferably by strips 9 integral with one of these plates and attached by the bolts 10 to the other thereof. It will be seen that there are side plates 3, 4 and 5 preferably so connected at each side 50 of the range. The upper plate 5 at each side, rests upon the corresponding plate 4 and is ordinarily held thereon by the mere weight of the structure, but may be attached in the same manner as indicated in

regard to plates 3 and 4 or otherwise, as 55 desirable.

The horizontal front or top of the range is formed by a top 11 having openings therein containing removable lids 12, 13 and 14 and the annular ring 15. This last is removable also and forms a support for the lid 14 in the well known manner. The lids permit access to the parts shown in Fig. 1 where the top of the range is shown broken away. 60

Within the frame and between the side plates 5, back plate 6 and face 8 I form a baking oven 16 spaced from the walls of the frame to allow vertical front and back passages or openings 17 and 18. Above the baking oven 16 the space between the top of the baking oven and the plate 7 provides a passage 19 into which open apertures 20 in the plates 5, which are provided for cleaning purposes. An aperture 21 in the plate 7 is 70 provided for the same purpose. I also provide apertures 22 in the side plates of the range for cleaning purposes. The oven 16 is available from either side of my range by means of doors 23 and 24 opening thereinto. 75 These are illustrated as closing openings made in the plates 5 and may be placed in one such plate only if desired. Below the oven 16 I have provided a hot closet 25 for dishes, etc. available by doors 26 and 27 and 80 for much the same purpose I provide a shelf 28. I strengthen the face 8 by means of ribs 29. 85

In the plate 3 of the side of my range I indicate the draft openings 30 opening into 90 the ash pit and which openings may be closed in any suitable manner.

In the front of my range I place doors 31 and 32 which are preferably vertically movable within suitable guides by means of handles 33 and 34 to permit access to fire pots having grates 35 and 36 upon which the main range fires are intended to be placed. Below the doors 31 and 32 I place preferably vertically movable doors 37 and 38 provided with handles 39 and 40, by means of which access is had to the ash pits 41 and 42. These ash pits have rear openings 43 and 44 in the back plate 6. The doors 37 and 38 also provide for other draft for the 100 fire pots having grates 35 and 36. 105

Between the fire pots and in the front part of the range I provide grate 45, which

is removable in a manner hereinafter described. It is intended as a broiling grate. The ash pit 46 is accessible by means of a preferably swinging door 47 hinged at 48 and 49 and provided with a suitable handle 50. This door permits draft to the grate 45 also. Above the door 47 I provide a door 51 by which access is had to an intermediate oven 52, having a removable bottom 53, which when removed permits access to the broiling grate and fire thereon through this door 51. The back 54 and upper and lower boundaries 55 and 56 of this oven 52 co-operate with other frame parts of the range 5 to produce passages or spaces 58, 57 and 59 respectively, by which gases from the main fires of the range are permitted access to and can surround the oven 52. The lower limiting surface of the space or passage 59 is the 10 plate 60. Openings 61 permit free passage of gas from the space 58 into the space 59. This structure is best seen in Fig. 3. The plates 56 and 60 are provided with flanged recesses 62 and 63. Within the recess 62 the removable oven bottom 53 is placed while the recess 63 holds the removable grate 45 in the lower part thereof, supporting the upper edge 64 of this grate and above this edge 64 seats a lid or plate 65. The space 59 15 below the oven and also the space 58 at the back of the oven are in communication with the broiling grate when the plate 65 is removed and a passage is thus provided for gases from the broiling grate, and from the lower openings 66 at each side by which the 20 space beneath the intermediate oven 52 is connected with the spaces 67 and 68, lying between the side walls of the intermediate oven and the fire pots upon either side. It 25 will be noted that when the plate 53 is in place this space 59 beneath the oven is not directly in communication with the interior of the oven, but that when it is removed the interior of the oven is in direct communication with the space. The inner walls 67 and 68' of the passages or spaces 67 and 68 constitute the side walls of the intermediate oven and reach back to the rear wall 58' of the space 58. Refractory material 69 is used 30 to protect the metal parts of the fire pots from injury by the fire therein.

On the upper side of the top 55 of the intermediate oven, as best shown in Fig. 1, and between this top and the top 11 of the 35 range I place guard strips 70 which project from the rear of the front portion of my range a considerable part of the distance to the front thereof. These perform a double function. They support the top of the range 40 and prevent gases from the main fire pots from passing through the aperture 71, under certain circumstances hereinafter described, without previously heating the oven 52. A damper 70' is used for the purpose of closing 45 the space between the ends of the strips

70 nearest to the front of the range, shutting off by this means the passage of gas from the fire pots on either side to the aperture 71 through the space between the strips 70 and enables these gases to be turned down 75 through passages 67 and 68, as hereinafter described, to heat the intermediate oven 52. The rear portions of the fire pots 72 and 73 are formed with passages 74 and 75 and the sides of these fire pots toward the intermediate oven 52 are provided with passages 76 and 77 for purposes hereinafter described.

At the rear of each of the fire pots 72 and 73 I preferably place a removable water back 78, see Figs. 1 and 4, which water back is 80 adapted to be inserted endwise in an aperture formed therefor in the plate 3. It is supported in any suitable manner. The water back 78 is provided with the usual connecting pipes 79 and 80 joining it to the 85 water boiler 81. Between the hot water back and the hot water boiler I place valves 82 and 83 in the pipes 79 and 80, by means of which valves the water can be cut off from the boiler 81 in case of requirement of 90 repairs or renewal of the water back 78, thus avoiding drainage of the hot water boiler. The upper portions of the spaces or passages 67 and 68 are provided with removable plates 84 and 85 which can be removed when 95 the damper 70' is put in place and which can be closed when the damper 70' is open. Some advantage would ensue from the opening of all of these at the same time but they are preferably arranged to have the damper 100 70' and the plates 84 and 85 used in the manner as stated, the damper being open when the plates are in place and closed when the plates are removed.

The operation is as follows:—The hot air 105 from the fire pots, when the plates 84 and 85 are in place, has access to the space above the intermediate oven and above the plates 84 and 85 and can flow around the ends of the strips 70 nearest to the front of the range 110 and through the space between these strips into and through the passage 71 when the damper 70' is open. This heats the top of the range and of course slightly heats the intermediate oven 52, heating the oven 115 16 also in its passage to the smoke pipe. The passages 74 and 75 carry but little of the gas or the hot air from the fire pots, as their path to the aperture 71 is more tortuous than the path just described. The gases from 120 passages 74 and 75 under these conditions must pass through the spaces 67 and 68 through the apertures 66 and out the apertures 61 into space 58 by which communication is had with the opening 71. Very little 125 of the hot air passes in this way, in consequence, the most of it passing by the shorter path across the top of the intermediate oven 52.

When the plates 84 and 85 are removed 130

and the damper 70' is closed, the gases and hot air formerly flowing across through the openings 76 and 77 cannot reach the aperture 71 through the previous path, but must flow down through the spaces 67 and 68 through the apertures 66 and back through the apertures 61 into the space or passage 58 following in this manner the same path as whatever gases previously flowed through the passages 74 and 75, but with this condition that no other path is then opened for hot air and gas from either of the fire pots than the one just named. The result of this is that the hot air and gas from both of the fire pots flows out through apertures 76 and 77 and passages 74 and 75 uniting in the spaces 67 and 68 and thus flow around and under the intermediate oven 52 heating it correspondingly. The action just named could take place of course whether or not the plates 53 and 65 were in place, but most advantageously with these so placed.

The broiling grate is intended to be used primarily with the plates 84 and 85 and finds its best use under these conditions. The plates 53 and 65 are then removed. Access is had to the top of the broiling grate through the door 51 and the opening otherwise covered by plate 53. The hot air and gases from the broiling grate find their escape through the space or passage 59, apertures 61 and space or passage 58. I have shown supports at the top of the passage 58 and a plate providing removable means for cutting off this passage when desired, confining the flow of gas to that which passes between the strips 70. In any event the ultimate passage of the hot air and gases through the aperture 71 insures that they shall pass through the passages 17 and 18 on their way to the chimney and shall heat the oven 16.

Having thus described my invention, what I claim as new and desire to secure by Letters Patent, is:—

1. In a device of the character described, a plurality of fire pots, an oven between said fire pots spaced from said fire pots and forming passages between said fire pots and 50 said oven, said oven having a removable bottom, a broiling grate below said removable bottom, and a removable top for said broiling grate.

2. In a device of the character described, a plurality of fire pots, an oven therebetween having a removable bottom, a wall beneath said oven forming a passage beneath said removable bottom, and having a removable plate therein and a removable grate beneath 60 said plate.

3. In a device of the character described, a plurality of fire pots having openings toward each other, an intermediate oven spaced from the fire pots to provide vertical 65 passages therebetween, a horizontal wall be-

neath the oven providing a horizontal passage connecting said vertical passages, said horizontal wall and the bottom of the oven each having an opening therein, and a grate beneath the opening in the horizontal wall. 70

4. In a device of the character described, a plurality of fire pots, an oven having an opening in its bottom and a horizontal wall having an opening therein beneath said oven, all forming a passage beneath the 75 oven and, communicating therewith, a plurality of vertical passages between the oven and the fire pots, removable plates for the openings in the oven and said horizontal wall, a broiling grate beneath the opening 80 in the horizontal wall, and means for closing the plurality of vertical passages.

5. In a device of the character described, a plurality of fire pots and an oven forming 85 a plurality of passages between said fire pots and said oven, a broiling grate beneath the oven, means for closing said plurality of passages, and a cover for the grate.

6. In a device of the character described, a plurality of fire pots, an oven between 90 them, a horizontal wall beneath the oven, having a removable plate therein, the fire pots, oven and horizontal wall forming a plurality of vertical passages between the fire pots and oven, and a horizontal passage 95 beneath the oven, a broiling grate beneath said horizontal wall, and means for closing the vertical passages.

7. In a device of the character described, a plurality of fire pots and an oven spaced 100 therebetween to form a plurality of vertical passages, a broiling grate beneath the oven, and a cover for the grate.

8. In a device of the character described, an oven, a fire pot having openings toward 105 the oven and spaced from the oven to provide a vertical passage therebetween, a lower limiting wall forming a space beneath the oven connected with said vertical passage, the bottom of the oven and a portion of the 110 lower limiting wall being removable, and a grate beneath the removable portion of the lower limiting wall.

9. In a device of the character described, an oven, walls spaced from opposite sides 115 of said oven to provide vertical passages on either side of the oven, a fire pot adjacent one of said walls and connecting with the passage formed between it and the oven, a lower limiting wall forming a space between 120 it and the oven and connecting with the vertical passage, a portion of the bottom of the oven and the lower limiting wall being removable, and a grate beneath the removable portion of the lower limiting wall. 125

10. In a device of the character described, a fire pot, an oven spaced therefrom to form a vertical passage between, a broiling grate beneath the oven, and a cover for the grate.

11. In a device of the character described, 130

a fire pot, an oven spaced therefrom to form a vertical passage between connecting with said fire pot, a horizontal wall forming a horizontal space beneath the oven in communication with the vertical space between it and the fire pot, a broiling grate beneath the oven, and a removable cover for the grate.

12. In a device of the character described, 10 a fire pot, an oven spaced therefrom at the side thereof, a vertical wall in the rear of the oven forming a passage between it and

the oven which is in communication with the smoke flue, an apertured horizontal wall beneath the oven forming a passage below said oven communicating with the side and rear vertical passages, a grate in said horizontal wall beneath the aperture, and means for closing the aperture. 15
